(57) **CLAIM**

The ornamental design for a hair cutting blade as shown and described.

DESCRIPTION

FIG. 1 is a front view of a first embodiment of a hair cutting blade, showing a first image in a sequence, showing my new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a second embodiment of a hair cutting blade, showing a first image in a sequence, showing my new design;

FIG. 8 is a front view of a second image thereof;

FIG. 9 is a front view of a third image thereof;

FIG. 10 is a front view of a fourth image thereof;

FIG. 11 is a front view of a fifth image thereof;

FIG. 12 is a front view of a sixth image thereof;

FIG. 13 is a front view of a third embodiment of a hair cutting blade, showing a first image in a sequence, showing my new design;

FIG. 14 is a front view of a second image thereof;

FIG. 15 is a front view of a third image thereof;

FIG. 16 is a front view of a fourth image thereof;

FIG. 17 is a front view of a fifth image thereof;

FIG. 18 is a front view of a sixth image thereof;

FIG. 19 is a front view of a fourth embodiment of a hair cutting blade, showing a first image in a sequence, showing my new design;
